UNITED STATES PATENT OFFICE.

HUGO JOHN, OF ILVERSGEHOFEN, NEAR ERFURT, GERMANY.

APPARATUS FOR CUTTING GIRDERS.

No. 823,871.

Specification of Letters Patent.

Patented June 19, 1906.

Application filed September 11, 1905. Serial No. 278,023.

To all whom it may concern:

Be it known that I, HUGO JOHN, manufacturer, a subject of the King of Prussia, German Emperor, residing at 1 Schwerbörnerstrasse, Ilversgehofen, near Erfurt, Germany, have invented certain new and useful Improvements in Apparatus for Cutting Girders, of which the following is a specification.

This invention relates to an apparatus for cutting girders, and especially I-girders, and differs from well-known apparatus of this character in that the girder when its two ends and two flanges are being cut need not be turned through an angle of one hundred and eighty degrees or ninety degrees, and, furthermore, the apparatus need not be moved. By this means considerable time and labor are saved in cutting girders, especially in the latter devices having great length. By turning a girder through an angle of one hundred and eighty degrees it is intended to be understood the manipulation of the girder in its longitudinal direction in such manner that, for instance, its former right-hand end becomes, after the turning, the left-hand end. In the same manner turning a girder through an angle of ninety degrees it is to be understood as turning the girder in its longitudinal direction, so that its two ends in the new position are shifted at a right angle relatively to the former position. This object is attained by an apparatus which will be more fully hereinafter set forth and having three upper and three corresponding lower cutters of a specific arrangement.

In the drawings, Figure 1 is a sectional elevation showing the position of the cutters with respect to the girder operated upon, parts being illustrated in dotted lines. Fig. 2 is a top plan view. Fig. 3 is a sectional end elevation. Fig. 4 is a detail perspective view of a portion of a girder, showing the manner of cutting the same, the removed parts being illustrated in dotted lines. Figs. 5 to 22, inclusive, illustrate different positions and sections of the girder during the cutting operation and as a result of the latter.

Similar characters of reference are employed to indicate corresponding parts in the views.

The two upper cutters *c* and *d* and the corresponding bottom cutters *c'* and *d'* are U-shaped and arranged in the apparatus in such manner that they are superposed with their front and back branches or arms in corresponding positions, a third straight cutter *e*,

with a corresponding bottom cutter *e'*, being also disposed in the apparatus so that their flat sides are parallel to the front and back arms of the two U-shaped cutters *c* and *d* and *c'* and *d'*, the cutters *e* and *e'* being, respectively, between the upper cutters *c* and *d* and lower cutters *c'* and *d'*.

The arrangement of the cutters is particularly shown by Figs. 1 and 3, and the apparatus includes a fixed holder *a* for the bottom tools and a movable holder *b* for the upper tools. These holders have narrow or top ends which carry the U-shaped cutters *c* and *d* and *c'* and *d'*; and on one of the longitudinal sides of each holder is arranged the straight cutters *e* and *e'*. The movable holder *b* for the upper tools is reciprocated by any suitable means toward the holder *a* for the bottom tools or cutters, the means employed for this operation being either manual or by power and may be either by pressure delivered from the top or by a pull from the bottom.

The operation of the apparatus is illustrated in Figs. 3 to 17 and is as follows: For instance, consider the I-girder shown in elevation and cross-section by Fig. 5, the cross-sections being indicated by *x* and *y*. The ends to be cut off or sheared off are marked 1, 2, 3, and 4.

Figs. 6 to 17 show the position of the I-section girder during the various steps of the cutting at both ends of the girder, Figs. 6 to 11 illustrating the cutting at the *x* end and Figs. 12 to 17 at the *y* end. These figures also show the positions of the girder relatively to the cutting apparatus and the working of the corresponding cutters, the several views being diagrammatic in their arrangement.

Figs. 6 to 9 show the cutting of the flange portions 1, 2, 3, and 4 by means of the cutters *d* and *d'*, which operate as shown by Fig. 3. During these four cutting operations the girder is at first standing twice in the position shown in full lines in Fig. 3 on the left-hand side, and then twice in the position shown in dotted lines on the right-hand side of the same figure. The cutting of the end *x* is effected in the following sequence. The right-hand U-shaped cutters *d* and *d'* (see Fig. 6) cut with their front arms and the web the bottom back flange 2. (See also Fig. 2.) In Fig. 7 the same cutters *d* and *d'* cut with their back arms and the web the front bottom flange 1. The girder is then rotated through an angle of one hundred and eighty degrees—

that is to say, moved about its longitudinal axis in such manner that the flange which was at the top now comes to the bottom. (See Fig. 18.) In Fig. 8 the same right-hand ⁵ **U**-shaped cutters *d* and *d'* cut with their back arms and the web, as in Fig. 7, the front flange 4 at the *x* end of the girder, which is now situated at the bottom. In Fig. 9 the cutters *d* and *d'* finally cut with their front ¹⁰ arms and the web back flange 3 at the *x* end of the girder and now also situated at the bottom. The girder is then rotated through an angle of ninety degrees (see Fig. 20) and is pushed by the cutters *d* and *d'* to the flat cutters ¹⁵ *e* and *e'*. These flat cutters operate to cut the web portions $3 \frac{1}{4} x$ and $1 \frac{1}{2} x$, which have been left between the two cut flanges. In Fig. 10 the cutters *e* and *e'* cut the web ²⁰ portions $3 \frac{1}{4} x$. Then the girder is rotated again through an angle of one hundred and eighty degrees. (See Fig. 21.) In Fig. 11 the same girders *e* and *e'* cut the web portions $1 \frac{1}{2} x$. In this way one end, *x*, of the girder has been completely cut and the same ²⁵ operations are repeated for the girder end *y*. In pursuing the operation with respect to the end *y* the girder is shifted in a longitudinal direction or so disposed until its *y* end comes level with the **U**-shaped cutters *c* and *c'*. As ³⁰ shown by Fig. 12, the **U**-shaped cutters *c* and *c'* first cut with their front arms and the web the bottom back flange $2 y$. In Fig. 13 the **U**-shaped cutters *c* and *c'* cut with their back arms and the web the bottom front flange $1 y$, ³⁵ and at the conclusion of the latter cutting operation the girder is then rotated through an angle of one hundred and eighty degrees. (See Fig. 13.) In Fig. 14 the **U**-shaped girders *c* and *c'* cut with their back arms and the web the ⁴⁰ front flange $4 y$, which is now situated at the bottom. In Fig. 15 the **U**-shaped cutters *c* and *c'* cut with their front arms and the web the bottom back flange $3 y$. The girder is then rotated through an angle of ninety degrees, ⁴⁵ Fig. 20, and again brought within the reach of the cutters *e* and *e'*. In Fig. 16 the cutters *e* and *e'* cut the remaining web por-

tion $3 \frac{1}{4} y$. The girder is then again rotated through an angle of one hundred and eighty degrees, Fig. 21. In Fig. 17 the cutters *e* and *e'* ⁵⁰ cut the remaining web portions $1 \frac{1}{2} y$, and by this means the girder end is completely cut. The cut girder end *x* is shown in Fig. 4 in perspective, and the same figure also shows the cut flange and web portions. Fig. 22 illustrates the movement of the beam operated upon to turn it through an arc of ninety degrees in a horizontal plane to show the position of the girder during the cutting operation. This turning of the girder brings the ⁵⁵ ends *l* and *r* at a right angle relatively to the former positions occupied by said ends, and demonstrates the edge of the cutters heretofore set forth in operating upon a girder without requiring a complete overturn of the ⁶⁰ same during certain cutting operations. The apparatus described therefore enables a girder to be cut at both ends without having to turn it and without having to turn the apparatus with its driving and other coöperating ⁶⁵ parts. ⁷⁰

Having thus described the invention, what is claimed is—

1. An apparatus of the class set forth, embodying two pairs of cutters of **U** shape arranged in upper and lower relation, the upper cutters being driven and the lower cutters fixed, and upper and lower straight cutters between the said **U**-shaped cutters and parallel to the arms of the latter. ⁷⁵ ⁸⁰

2. An apparatus for cutting **I**-section girders characterized by an upper pair of driven cutters, a lower pair of fixed cutters, the cutters being of **U** shape and similarly arranged to coöperate with each other, and upper and lower straight cutters. ⁸⁵

In testimony whereof I have hereunto set my hand in presence of two subscribing witnesses.

HUGO JOHN.
